US00D882105S

(12) **United States Design Patent** (10) Patent No.: **US D882,105 S**
Lee et al. (45) Date of Patent: **** Apr. 21, 2020**

(54) **ADULT TOY**

(71) Applicant: **EIS GmbH**, Bielefeld (DE)

(72) Inventors: **Won-Gyung Lee**, Hamburg (DE);
Johanna Konigsberger, Hamburg (DE); **Paul Fally**, Hamburg (DE); **Jan Meissner**, Hamburg (DE); **Tobias Schreier**, Hamburg (DE)

(73) Assignee: **EIS GmbH**, Bielefeld (DE)

(**) Term: **15 Years**

(21) Appl. No.: **29/711,564**

(22) Filed: **Oct. 31, 2019**

Related U.S. Application Data

(62) Division of application No. 35/504,819, filed on Oct. 25, 2017 (U.S. filing date under 35 U.S.C. 384), and having an international filing date of Oct. 25, 2017, now Pat. No. Des. 868,281.
